RECORDING MECHANISM

Earl M. Allen, Swissvale, Pa., assignor to The Union Switch & Signal Company, Swissvale, Pa., a corporation of Pennsylvania

Application September 25, 1935, Serial No. 42,020

7 Claims. (Cl. 246—107)

My invention relates to recording mechanism, and is particularly well adapted for, but not limited to, mechanism for recording the progress and speed of trains along a railway, and for recording signal operations.

One feature of my invention is the use of a normally stationary recording mechanism which operates only upon the passage of a train of which a record is to be made. This feature of my invention, when utilized with mechanism of the recording tape type permits the tape to remain stationary until a record is to be made and then to be moved at a relatively high speed during the recording so that a clear and legible record is produced without wasteful use of the tape.

I will describe one form of recording mechanism embodying my invention, and will then point out the novel features thereof in claims.

In the accompanying drawings, Fig. 1 is a diagrammatic view illustrating one form of recording mechanism embodying my invention as applied to a layout wherein one track is intersected by another track. Fig. 2 is a view illustrating a portion of tape with the record made thereon by the apparatus shown in Fig. 1.

Referring first to Fig. 1, the reference characters X and Y designate two intersecting railway tracks. The rails 1 and 1A of track X are divided by means of insulated joints 2 into track sections 1T, 2T, and 3T. Similarly, the rails 1 and 1A of track Y are divided by means of insulated joints 2 into track sections 4T, 5T, and 6T. The sections 1T, 3T, 4T, and 6T, I shall term approach sections, and sections 2T and 5T I shall term detector sections. The detector sections 2T and 5T include the intersection Z.

Each track section 1T, 2T, 4T, and 5T is provided with a track circuit including a battery 3 connected across the rails at one end of the section and with a track relay connected across the rails at the other end of the section and designated by the reference character R with the same prefix as that used in the reference character for the associated section.

The reference characters 1S and 3S designate traffic controlling devices, here shown as signals, for governing traffic moving over track X, and the reference characters 2S and 4S designate similar signals for governing traffic moving over track Y.

Signals 1S and 2S control contacts 8 and 9, respectively, in such a manner that each contact is closed only when the associated signal is in its stop condition as shown in the drawings.

The reference characters 1H and 2H designate

two signal indication relays which are controlled by the contacts 8 and 9, respectively, each of the relays being energized only when the associated contact is closed.

The reference character Q designates a control relay governed by relays 1TR, 2TR, 4TR, 5TR, 1H, and 2H.

Associated with the relay Q is a repeating relay designated by the reference character P and having a slow pickup characteristic.

In order to obtain a record of train movements on the tracks X and Y and of the operation of signals 1S and 2S, I provide a tape 30, which may be of paper or other suitable material, and which passes over drums 31, 31. This tape is unwound from a roll 32 onto a drum 33 by means of suitable mechanism operating the latter drum. As here shown, this mechanism comprises a motor M connected with drum 33 by a chain of gears 34.

The tape 30 is preferably provided with time divisions 35 corresponding to the rate at which the tape is moved by the motor M.

In order to secure a record of the progress of trains through each block 1T, 2T, 4T, and 5T, and of the position of signals 1S and 2S, I provide each section and each signal with a recording device designated by the reference character E with the same prefix as that used in the reference character for the relay associated with such section or signal. As here shown, each recording device comprises a magnet 36, and a pivotally mounted member 37 biased by any suitable means such, for example, as by a spring 38 to a position away from the magnet. Rigidly attached to the member 37 is a stylus 39, which may, for example, be a pencil, which pencil is adapted to trace a record on tape 30. The magnet 36 and member 37 are so disposed that the pencil 39 is moved transversely across the tape 30 towards the magnet when the magnet is energized and away from the magnet to a normal position, as shown in the drawings, when the magnet is deenergized. Each magnet 36 is provided with a circuit which includes a back contact 24, 25, 26, 27, 28, or 29 of the associated R or H relay.

The pencils 39 are preferably so located that the records made thereby on the tape at any given instant are directly opposite each other.

The reference character J designates a time controlled printing device which when energized stamps the date and time on the tape 30. The device J is preferably so located that the stamping of the tape will be substantially in line with the pencils 39. A number of such date and time

stamping devices are well known and, since the form of such device is in no way involved in my invention, no detailed explanation of the operation of such device is being given herein.

5 The manner in which the apparatus operates will best be understood by tracing the circuits and describing the operation of the various parts simultaneously.

10 With all apparatus in the normal condition as shown in the drawings I shall assume that a train moving from left to right on track X enters section 1T so that track relay 1TR becomes released. When relay 1TR is released, magnet 36 of recording device 1TE will become energized by the 15 closing of back contact 24 of relay 1TR, and relay Q will be released by the opening of a circuit which passes from terminal B of a suitable source of energy through front contacts 12, 13, 14, 15, 16 and 17 of relays 4TR, 1TR, 2H, 1H, 5TR, 20 and 2TR, respectively, and relay Q to terminal C of the same source of current. When relay Q is released, the closing of its back contact 21 will energize slow pickup relay P, and will also energize the device J through the back point of contact 22 of relay P so that the date and time will be stamped on tape 30. When relay P becomes picked up so that energy is transferred from the back point to the front point of contact 22, current will be first cut off from device J and will be 25 then supplied to motor M (by virtue of a circuit which passes from terminal B through back contact 21 of relay Q, front point of contact 22 of relay P and motor M to terminal C) so that motor M will drive drum 33. The movement of drum 33 will cause the movement of tape 30 so that the pencils 39 will draw a record thereon. All pencils will draw straight lines in their normal paths except the pencil of recording device 1TE which pencil will draw a line parallel to but to one side of its normal path because its magnet 36 is energized.

30 It should be noted that the slow pickup characteristic of relay P insures that device J will have ample time to stamp the tape 30 before the movement of the tape is initiated by motor M.

35 Although for the sake of simplicity I have not shown in the drawings the control circuits for the signals, such signals usually will be so controlled as to normally indicate "stop", and to change to "proceed" when the track relay for the associated approach section is released provided, of course, that traffic conditions in the vicinity of the intersection Z are such as to make such proceed indication safe for a train accepting the indication.

40 Therefore, when a train enters section 1T, so that relay 1TR becomes deenergized, signal 1S will change to "proceed" and will open contact 8 so that indication relay 1H will become released. When relay 1H is released, magnet 36 of recording device 1HE will become energized so that its pencil 39 will draw an offset line to one side of its normal path.

45 The tape at this time will show that section 1T is occupied, that signal 1S is indicating proceed and the date and time at which the train entered section 1T.

50 When the train enters section 2T so that relay 2TR becomes released, magnet 36 of recording device 2TE will become energized so that its pencil will draw an offset line on the tape. The tape now indicates that the train has just entered section 2T.

55 When signal 1S returns to its stop condition, relay 1H will again be energized by the closing of contact 8. When relay 1H is energized, magnet

36 of recording device 1HE will become deenergized so that pencil 39 of recording device 1HE will again draw a line on the tape in its normal path. The tape now indicates that the train is bridging sections 1T and 2T, that all other sections are unoccupied and that all signals are displaying their normal stop indication.

60 When the train departs from section 1T so that relay 1TR becomes energized, magnet 36 of recording device 1TE will be deenergized to cause 10 pencil 39 of recording device 1TE to move back to its normal position. The tape now indicates that all sections except section 2T are unoccupied, and that all signals are displaying the stop indication.

15 When the train leaves section 2T, relay 2TR will become energized, so that magnet 2TE will become deenergized and relay Q will become energized. When magnet 2TE is deenergized pencil 39 of magnet 2TE will move back to its normal 20 position. When relay Q is energized, current will be cut off from motor M and relay P will become deenergized. Thus the movement of tape 30 will cease and the tape at this time will indicate that all apparatus is again in its normal condition 25 ready for the next train movement.

30 Although I have herein described but a few of the operations of the apparatus embodying my invention, it will be readily apparent as to how the apparatus will function for any possible train movement.

35 Although, for the sake of simplicity, I have not shown the signals 3S and 4S and track sections 3T and 6T as being provided with recording devices, it will be understood that these signals and track sections usually will also be so equipped.

40 Referring now to Fig. 2, the portion of the tape 30 here shown bears a record which may be explained as follows: at 11 a. m. of July 7, 1935, section 1T became occupied by a train, and at approximately two seconds after 11 a. m., signal 1S was caused to indicate proceed. The tape further discloses that at approximately 11:01 a. m., the train entered section 2T and at approximately two seconds after 11:01 a. m., signal 45 1S was caused to again assume its stop condition. At approximately twenty seconds after 11:01 a. m., the train departed from section 1T and at approximately forty seconds after 11:01 a. m., the train departed from section 2T. The tape, therefore, discloses a full and complete record of the movement of this train and of the observance of the signal by the engineman. It is apparent that the speed of the train through each block can be very readily determined from the 55 tape if desired.

55 In the event of a collision at the intersection Z, the responsibility for such collision can very readily be determined from the tape since the time of arrival of each train in the approach and detector sections will be recorded together with the indications displayed by the signals governing the colliding trains.

60 It will be seen from the foregoing description of the operation of the apparatus embodying my invention that, since the record tape moves only when required to record the movements of a passing train, the speed of the tape may be relatively fast so as to produce a clear and legible 70 record without resulting in excessive use of tape.

65 Although I have herein shown and described only one form of apparatus embodying my invention, it is understood that various changes and modifications may be made therein within the 75

scope of the appended claims without departing from the spirit and scope of my invention.

Having thus described my invention, what I claim is:

5. 1. In combination, a section of railway track provided with a track relay, a record tape, means controlled by said track relay for recording the condition of such relay on said tape, mechanism effective when energized to move said tape at a predetermined speed, a device effective when energized to record the date and time on said tape, a slow pickup relay normally occupying a released condition, means for energizing said slow pickup relay when said track relay is released, 5 means for energizing said device when both said slow pickup relay and said track relay are released, and means for energizing said mechanism as long as said slow pickup relay is picked up provided said track relay is released.
10. 2. In combination, a section of railway track provided with a track relay, a record tape, a stylus arranged to trace a record on said tape, a magnet for controlling said stylus, means including a back contact of said track relay for controlling said magnet, mechanism effective when energized to move said tape at a predetermined speed, a device effective when energized to record the date and time on said tape, a slow acting relay normally occupying an initial condition but capable of assuming an operated condition, means for causing said slow acting relay to assume its operated condition when said track relay is released, means for energizing said device when said slow acting relay is in its initial condition provided said track relay is released, and means for energizing said mechanism as long as said track relay is released provided said slow acting relay is in its operated condition.
15. 3. In combination, a section of railway track, an indicating relay which becomes released when said section is occupied, a record tape, means controlled by said indicating relay for tracing a record on said tape to correspond with the condition of such relay, mechanism effective when energized to move said tape at a predetermined speed, a device effective when energized to record the date and time on said tape, a slow pickup relay normally occupying a released condition, means for energizing said slow pickup relay when said indicating relay is released, means for momentarily energizing said device when both said slow pickup relay and said indicating relay are released, and means for energizing said mechanism as long as said slow pickup relay is picked up provided said indicating relay is released.
20. 4. In combination, a section of railway track, a signal for said section having an initial condition, an indicating relay which is picked up as long as said signal occupies its initial condition, a record tape, means controlled by said relay for tracing a record on said tape to correspond with the condition of said relay, mechanism effective when energized to move said tape, a device effective when energized to record the date and time on said tape, a slow pickup relay normally occupying a released condition, means for energizing said slow pickup relay when said auxiliary relay is released, means for energizing said device when both said auxiliary relay and said slow pickup relay are released, and means for energizing said mechanism when said slow pickup relay is picked up provided said auxiliary relay is released.
25. 5. In combination, a section of railway track including a track relay, a signal for said section having an initial condition, an indicating relay which is picked up as long as said signal remains in its initial condition, a record tape, means for recording correlative on said tape the condition of said track relay and the condition of said indicating relay, mechanism effective when energized for moving said tape at a predetermined speed, a device effective when energized to record the date and time on said tape, an auxiliary relay which becomes released whenever either the track relay or the indicating relay is released, a slow pickup relay normally occupying a released condition, means for energizing said slow pickup relay when said auxiliary relay is released, means for energizing said device when both said auxiliary relay and said slow pickup relay are released, and means for energizing said mechanism when said slow pickup relay is picked up provided said auxiliary relay is released.
30. 6. In combination, a plurality of sections of railway track each including a track relay, a record tape, means for recording correlative on said tape the condition of each track relay, mechanism effective when energized to move said tape at a predetermined speed, a device effective when energized to record the date and time on said tape, an auxiliary relay which becomes released whenever any of said track relays are released, a slow acting relay normally occupying an initial condition but operable to another condition when energized, means for energizing said slow acting relay when said auxiliary relay is released, means for energizing said device when said auxiliary relay is released provided said slow acting relay is in its initial condition, and means for energizing said mechanism when said auxiliary relay is released provided said slow acting relay is in its other condition.

EARL M. ALLEN.
